(No Model.)

W. W. HAAS.

CALENDAR.

No. 392,327.

Patented Nov. 6, 1888.

FIG. 1.

UNITED STATES PATENT OFFICE.

WILLIAM W. HAAS, OF NEWTON, KANSAS.

CALENDAR.

SPECIFICATION forming part of Letters Patent No. 392,327, dated November 6, 1888.

Application filed April 3, 1888. Serial No. 269,421. (No model.)

To all whom it may concern:

Be it known that I, WILLIAM W. HAAS, a citizen of the United States, residing at Newton, in the county of Harvey and State of Kansas, have invented new and useful Improvements in Calendars, of which the following is a specification.

My invention relates to improvements in calendars; and it has for its objects to provide a perpetual calendar in which the adjustment for the various months and years will be simple and easily understood.

With this object in view the invention consists in a calendar in which the only adjustment necessary is the movement of a small slide or tablet bearing the days of the month from 1 to 31.

The invention is more fully described hereinafter in connection with the accompanying drawings, wherein—

Figure 1 is a front view of the improved calendar adjusted for March, 1888. Fig. 2 is a detail vertical sectional view through the slide or tablet.

Referring to the drawings, the card or body of the calendar A may be of any desired shape, (preferably rectangular,) and may be ornamented in any preferred manner, and it is provided near its lower end with the horizontal slot B. The table C contains the names of the days of the week from Sunday to Friday of the following week, (thirteen days,) and they are arranged in a horizontal series parallel with the slot B and just above the same. Below the slot B a similar table is arranged, the only difference being that the names in this table extend from Monday to Saturday of the following week, (thirteen days.)

E represents a slide or tablet, which bears against the face of the card or calendar between the day-tables C D, and is provided on its rear side with a button, F, which bears against the rear side of the card or calendar and has a shank sliding in the slot B. On this slide or tablet are arranged the days of the month in horizontal series, seven days being arranged in each series. This slide may be adjusted at any part of the slot B to bring the figure 1 thereon under any day of the week from Sunday to the following Saturday, the remaining six figures in the horizontal series falling under the six week-days following the one indicated by the first figure. (The lower

table, D, being arranged similarly to the upper table, with the exception mentioned above, 55 the days of the week may also be indicated thereon.)

Above the upper day-table and to the left of the card A is arranged a year-column, G, containing the following years: 1888, 1889, 60 1890, 1891, 1892, 1894, and 1898, and after each of the said years is arranged a series of years, which may be extended at will. The years given in full on the left are sample years, and any year outside of this series may 65 be compared with one of these. For instance, 1882, 1893, and 1899 are identical with the year 1888, and the calendar of one may be taken for the others. The same is true of the years 1894, 1877, 1883, and 1900, and also of 7c 1891, 1874, 1880, and 1885. This column of years constitutes a table to which any year, either in the past or future, may be referred.

Opposite the years above mentioned and over the day-tables are arranged the names 75 of the months in the following manner: Over Sunday of the upper day-table are arranged the names of the months whose first days come on Sunday. Over Monday are arranged the names of the months whose first days come on Monday, and so on through the entire table. For instance, in 1888 over Sunday are arranged January and October; over Monday is arranged May; over Tuesday is August; over Wednesday are February, March, and 80 November; over Thursday is June; over Friday are September and December, and over Saturday are April and July. The months following the other years are similarly but not identically arranged.

90 The operation of the calendar is as follows: On the first day of each month adjust the figure 1 of the slide or tablet under the required month which appears opposite the required year. In case of leap-years, the upper day-table will indicate the days of the week for the first two months, (January and February,) after which the lower table must be used throughout the year.

Under the lower day-table are arranged the 100 directions for operating the calendar, and it will be apparent that it is so simple as to be readily understood.

Having thus described my invention, I claim—

1. In a calendar, the day-table C, the year-

column, the months arranged opposite the years and above the day-table, and the slide having the days of the month, substantially as specified.

5 2. In a calendar, the day-table C, the day-table D, the adjustable slide or tablet between the said tables and carrying the days of the month, the year-column, and the months opposite the years and over the day-tables, all ar-

ranged substantially as and for the purpose to specified.

In testimony that I claim the foregoing as my own I have hereto affixed my signature in presence of two witnesses.

WILLIAM W. HAAS.

Witnesses:

ETHEL M. HAAS,
G. L. HAAS.
